UNITED STATES PATENT OFFICE.

VALENTINE G. SCHUCK, OF NEW YORK, N. Y., ASSIGNOR TO THE SUTRO BROTHERS BRAID COMPANY, OF NEW YORK.

DESIGN FOR BRAID.

SPECIFICATION forming part of Design No. 18,889, dated January 29, 1889.

Application filed November 23, 1888. Serial No. 291,685. Term of patent 14 years.

To all whom it may concern:

Be it known that I, VALENTINE G. SCHUCK, of the city, county, and State of New York, have invented and produced a new and original Design for Braid; and I do hereby declare that the following is a full and exact description thereof, reference being had to the accompanying drawing, and to the letters of reference marked thereon, making a part of this specification.

This new design is illustrated in said drawing by a plan view, on an enlarged scale, of a piece of braid ornamented therewith.

The braid, in the customary form of a narrow extended strip, A, is indented with lines forming a central zigzag, B, having each branch thereof following the length of the braid in the one direction extended, as at c c, beyond the angle formed therewith by the next line in advance and prolonged out to the margin of the braid. The spaces bounded by the lines of the zigzag B and the extensions c c thereof are filled in and subdivided

each by a series of diverging lines, e e, forming a herring-bone pattern whose angles are 25 symmetrically disposed and are bisected by a central line, d, drawn parallel with the lateral lines c c of said spaces, as shown in the drawing.

What I claim is—

The design herein shown and described for the ornamentation of braid, the same consisting of a central zigzag extending the length of the braid, and whose broken lines are severally prolonged each in the same direction to 35 the outer margin of the braid, the intervening spaces being severally filled in with the diverging lines of a herring-bone pattern.

In testimony whereof I have signed my name to this specification in the presence of two 40 subscribing witnesses.

VALENTINE G. SCHUCK.
